UNITED STATES PATENT OFFICE.

POLLOCK BARBOUR, OF LOUISVILLE, KENTUCKY.

BRIDLE-BIT.

SPECIFICATION forming part of Letters Patent No. 319,439, dated June 9, 1885.

Application filed November 17, 1884. (No model.)

To all whom it may concern:

Be it known that I, POLLOCK BARBOUR, a citizen of the United States, residing at Louisville, in the county of Jefferson and State of Kentucky, have invented a certain new and useful Improvement in Bridle-Bits; and I do hereby declare that the following is a full, clear, and exact description of the construction and operation of the same, reference being had to the accompanying drawings, forming part of the specification.

This my invention relates to certain new and useful improvements in bridle-bits, consisting in a bit having a solid snaffle-bar without joint in the center, but is slightly curved, with rings in the ends for the cheek-reins, and through which the curb-chain passes, which is made in the form of a chain, the central part of which consists of four or more links, connecting with slightly-curved bar-links, having rings in the outer ends, with the bars resting within the snaffle-rings to answer as levers in operating the curb.

The object of this my invention is to provide a bridle-bit that will be cheap, simple in construction, and effective in preventing horses from running away, and also to prevent them from breaking the bridle by pulling backward by the severity of the curb, which may be adjusted to cause any required degree of severity, or may be used in the same manner as an ordinary snaffle-bit. I attain the above object by the mechanism illustrated in the drawings, in which—

Figure 1 is a perspective view of the device, showing the peculiar construction of the curb. Fig. 2 is a perspective view of a portion of the curb, showing the leather covering of the chain.

Similar letters refer to similar parts throughout the several views.

In the drawings, A represents the bar of the snaffle-bit, which is made slightly curved, with rings B B in the ends for the check-reins, and through which the ends of the curb passes 45 without being attached thereto, but is held in its place by the rings C C in the ends.

D D are the bar-links or levers of the curb, which are made in form as shown in the drawings, with rings C C in the outer ends, which 50 are slightly turned down where they rest in the rings of the snaffle-bit, while the inner ends connect with the chain E, which consists of four or more links, and are intended to answer as levers to operate the curb, which may be 55 covered with leather F, when necessary to relieve its severity. This chain E may be removed and a bar-link substituted when necessary to render the curb more severe. The bar-links D of this device are intended to answer 60 as levers for operating the curb by forcing the chain E up against the under jaw of the horse, and thereby closes the rings B B of the snaffle against the sides of the jaw by means of the draft upon the reins. Therefore 65

What I claim as my invention, and desire to secure by Letters Patent, is—

1. A detachable curb for bridle-bits, consisting of the curved lever-links D D and rings C C and intermediate chain, E, adapted to co-operate with a bridle-bit, substantially as set forth. 70

2. The combination, with a bridle-bit, having end rings, of a curb composed of the curved lever-links, the intermediate chain, and 75 the end rings, all substantially as set forth.

POLLOCK BARBOUR.
